SELF-LOCKING WRENCH

August A. Westman, Carnation, Wash.

Application August 20, 1946, Serial No. 691,771

1 Claim. (Cl. 81—84)

1

This invention relates to a self-locking wrench and, more particularly, to a wrench of the self-locking type.

It is among the main objects of this invention to provide a wrench which may be either operated as a conventional "monkey" wrench or as a self-locking wrench which will tightly grip between its jaws an object to be held or turned.

It is another object that both of these functions be embodied in a single unitary structure that is simple, yet ruggedly constructed of few parts that are easily assembled and which may be manipulated with facility to vary the setting of the jaws of the wrench.

A further object is to provide, in a wrench of the type described, gripping elements that are relatively movable to each other and will not be deleteriously affected by extreme usage under conditions normally beyond the limits of the initial design.

The foregoing objects, and others ancillary thereto, I prefer to accomplish as follows:

According to a preferred embodiment of my invention, I associate with a wrench of the type wherein there is a main handle having a slidably movable jaw that is adjustable by the operation of screw means, a second gripping element which is pivoted to said handle in opposition to the movable jaw and is caused to swing about a pivot by a second handle pivotally connected to said pivoted jaw through the function of self-locking means between the main handle and the second handle. More specifically, the pivoted jaw is mounted astraddle a head on the first or main handle and the gripping face, by means of the pivoted connection to the head, swings toward and away from the slidably movable jaw in a closing or opening operation. The self-locking means for bringing the jaws into closed or gripping position and maintaining that position is suitably provided by a toggle-link pivotally connected between the one and the other handle. With such a construction it is possible to have a conventional wrench having its jaws adjusted for close, but not a gripping, engagement with an object to be turned, such as a nut or a square bar, and yet by making a slight adjustment and opening the jaws, the same may be closed about a similar sized object with a severe gripping action being had thereon, or the tool may be used as pliers.

The novel features that I consider characteristic of my invention are set forth with particularity in the appended claim. The invention itself, however, both as to its organization and its method of operation, together with additional

objects and advantages thereof, will best be understood from the following description of a specific embodiment when read in connection with the accompanying drawings, in which:

Fig. 1 is a face view of my wrench;

Fig. 2 is a fragmentary sectional view taken on line 2—2 of Fig. 1;

Fig. 3 is an edge view taken as though from the plane suggested by line 3—3 of Fig. 1; and

Fig. 4 is a cross-sectional view on line 4—4 of Fig. 1.

My wrench comprises the first or main handle 10 having the head portion 12 on one end. In the particular showing of Fig. 1, head portion 12 has a shank 14 which is inserted in the space between the legs of the generally U-shaped handle member 10 to be there secured by means of rivets 16, 16. A guide face 18 on the head 12 is shown as being inclined transversely across the general longitudinal axis of the handle 10, but it will be apparent that the same may be at right angles thereto or at a greater inclination, as desired. In the guide face 18 is formed an undercut groove 20 in which slides the rack 22, having teeth 24. A gripping jaw 26 is rigidly secured to the rack 22 by web 28 which extends therebetween and through the narrow or restricted portion 30 of the undercut groove 20. A worm hub 32 having spiral thread elements 34 is mounted in opening 36 of the head 12 and so positioned that the thread elements 34 are engaged in the teeth 24 of the rack 22.

By reason of the foregoing construction it will be apparent that the jaw 26 is slidably movable along the guiding face 18 upon rotation of the worm hub 32. Depending upon the direction of rotation, the jaw will either move to the left or to the right in Fig. 1.

A second jaw element 40, bifurcated to straddle a connecting portion of the head 12, is mounted on pivot pin 42 so that the gripping face 44 is in opposition to jaw element 26. Jaw 40 has a pair of bowed legs 48, 48, which extend downward or away from the pivot 42 on either side of the head 12 to a point where they are joined by pivot pin 50 to a second or swinging handle 52, which lies generally alongside of the main handle 10 in a closed position, but which swings outward relative thereto in the open position, as indicated by the solid and dotted line showing of Fig. 1.

Between the handle members 10 and 52 is positioned a toggle link 54, which is rigid and functions as an overthrow or self-locking element when the jaw 44 is closed toward the jaw 26. The link 54 is pivotally connected to handle 52 by

the pin 56 and, similarly, link 54 is connected to handle 10 by pivot pin 58. Considering that the latter pin 58 is a fixed pivot, pin 56 becomes a moving pivot. When handle 52 swings from the open to the closed position, the general tendency is to elongate the distance between pin 58 and pin 50 of the second jaw element 40, thereby causing the latter, in the showing of Fig. 1, to swing counterclockwise toward the gripping position. By so arranging the assembly that pins 50, 56 and 58 come into alignment, or that pin 56 moves slightly closer to handle 10 and head 12 than a straight line distance between 50 and 58, the self locking action is obtained.

If the object to be gripped between the jaws 26 and 44 is very thin, it will be quite obvious that rotation of the worm hub will be necessary so that a narrow spacing can be provided in the closed position. Similarly, when it is desired to grip a fairly large object the jaws will be moved quite wide apart by a reverse rotation of the worm hub 32.

I have found that, without difficulty and without extremely precise workmanship or adjustment, this wrench can with equal facility grip objects from the thickness of a sheet of paper or human hair up to and including all objects which can be disposed between the jaws 26 and 44 in their widest adjustment. If the adjustment is such that the jaws only close together a sufficient distance so that pivot 56 will not move across the line between 50 and 58 toward handle 10 and head 12, or even into that alignment, the tool functions as a pair of pliers or a "monkey" wrench.

While I have shown and described particular embodiments of my invention, it will occur to those skilled in the art that various changes and modifications may be made without departing from the invention, and I therefore aim in the appended claims to cover all such changes and modifications as fall within the true spirit and scope of my invention.

Having thus described my invention, I claim:

A self-locking wrench, comprising: a first handle; a second handle; a toggle link; a pivoted jaw element; a head on said first handle, said head

having a connecting portion extending to one side; said jaw element being bifurcated from one end toward the other end and mounted on said connecting portion in a straddling position and pivotally connected thereto at a first pivot point; said head having a slidable jaw element mounted therein; means for adjusting the initial position of said slidable jaw; said slidable and pivoted jaw elements having opposed rough jaw faces; one end of said second handle being pivotally connected to the bifurcated end of said pivoted jaw element at a second pivot point; one end of said toggle link being pivotally connected to said second handle at a third pivot point; the other end of said toggle link being pivotally connected to said first handle at a fourth pivot point; the jaw face of said pivoted jaw element being substantially parallel to a line between said first and second pivot points; said jaw faces being substantially parallel and said handles being substantially parallel when said second, third and fourth pivot points lie on a first common straight line in a locked position; lines connecting in order said first, second and third pivot points forming a large obtuse angle when said second, third and fourth pivot points lie on said first common line; said jaw faces being at a small acute angle one to another when said first, second and third pivot points lie on a second common straight line; and lines connecting in order said second, third and fourth pivot points forming a large obtuse angle when said first, second and third pivot points lie on said second common line.

AUGUST A. WESTMAN.
